ARTHUR T. PRESCOTT, OF EAST ORANGE, NEW JERSEY, ASSIGNOR TO GEORGE H. FROTHINGHAM CO., OF NEW YORK, N. Y., A CORPORATION OF NEW YORK.

MOORING-WINCH.

1,171,540.

Specification of Letters Patent. Patented Feb. 15, 1916.

Application filed March 24, 1913. Serial No. 756,456.

To all whom it may concern:

Be it known that I, ARTHUR T. PRESCOTT, a citizen of the United States, and a resident of East Orange, county of Essex, and 5 State of New Jersey, have invented certain new and useful Improvements in Mooring-Winches, of which the following is a specification, reference being had to the accompanying drawings, forming a part thereof.

10 My invention relates to electric motor driven winches and has special reference to such as are adapted for use in mooring ferry boats to bridges and like purposes.

In my co-pending application Serial Number 636,657 filed July 3, 1911, I have set forth and described a device of the aforesaid character in which an overload safety release mechanism is employed for permitting the parts to slip and the motor to 20 continue to operate when the pulling in load becomes excessive as for example when the boat strikes the end of the bridge. A lost motion connection is also set forth in the aforesaid application for starting the unwinding motion of the winch in order to insure the release of the jammed gears of the mechanism.

30 The object of my present invention is to provide a simple and improved device of the same character in which the safety release mechanism and the lost motion connection are both unnecessary.

Other objects will be set forth hereinafter.

I will describe my invention in the following specification and point out the novel features thereof in appended claims.

Referring to the drawings: Figure 1 is a 40 sectional elevation of a motor driven winch constructed in accordance with my invention. A diagrammatic view of a system of control adapted for governing the winch motor and arranged in accordance with my invention is shown in Fig. 2. Fig. 3 is a partially sectional plan view of the mechanism 45 of Fig. 1 with the clutch lever and its guide omitted and parts of the casing broken away to disclose the gearing. Fig. 4 is a sectional elevation of the limit switch actuating mechanism shown in plan in Fig. 3.

50 Like characters of reference designate corresponding parts in all the figures.

Referring particularly to Figs. 1, 3 and 4, a machine is shown mounted on a base 10 on which is also mounted an electric motor 11 having a shaft 12 which extends into

a casing 13 inclosing other parts of the mechanism.

A winding drum 15 is rotatively supported in bearings 16, 16 with its axis of rotation transverse to that of the motor shaft. 60 A worm wheel 18 affixed to the drum 15 at one end meshes with a worm 19 which is mounted on a shaft 20. This shaft is coaxial with the motor shaft 12 and extends longitudinally of the mechanism. It is rotatably mounted in bearings 21 and 22.

A sleeve 23 to which is secured a member 24 of a jaw clutch and a bevel gear 25 is arranged to slide on shaft 20 near one of its ends, but is splined to it or otherwise prevented from rotating on the shaft. A co-operating member 26 of the jaw clutch is secured to the adjacent end of the motor shaft 12 within the casing 13.

The gear case 30 protects the worm wheel 75 18 and a bracket 31 which is secured to or may be integral with the base 10, is arranged to guide a flexible rope or cable onto and off of the winch drum 15. A substantially vertical shaft 35 is mounted in suitable bearings 36 in a vertical standard 37. A bevel gear 38 is secured to the upper end of the shaft 35 and a bevel gear 39 is secured to its lower end in position to mesh with the bevel gear 25 when the sleeve 23 is adjusted to its 80 right hand position by means of a lever 40. When the sleeve is adjusted in the opposite direction the clutch members 24 and 26 are thrown into engagement, the arrangement of parts being such that either the motor 11 85 or the shaft 35 is operatively connected to the shaft 20 on which the worm 19 is mounted. Near the top of the standard 37 is a horizontal shaft 44 to which is secured a hand wheel 45 and a bevel gear 46 which 90 meshes with the bevel gear 38.

The lever 40 is pivotally supported at 48 and is provided with a grip 49 which is connected to a pawl or pin 50 and is arranged to release the pawl in a well known manner, 100 when the end of the lever and the grip are grasped by the hand of the operator. The pawl 50 is arranged to engage a notch 51, provided in a stationary sector 53, when the clutch members 24 and 26 are in engagement 105 and a notch 52 when the bevel gears 25 and 39 are in mesh. The pitch of the worm 19 and the worm wheel 18 is low so that the drum cannot over haul the shaft 20.

As shown in Fig. 3, the shaft of the wind- 110

ing drum 15 is provided with an extension 55 on which is rotatably mounted a sheave 56 and a substantially rectangular frame 57 which is integral therewith. A section of 5 the shaft extension is screw-threaded and is provided with a traveling nut 58 and a relatively stationary adjustable nut 59, the position of which on the shaft extension may be maintained by a set screw 60.

10 As shown in Fig. 4, the sheave 56 is provided with a cam 62 which projects from its inner surface and is arranged to actuate the arm 63 of a switch member 64. The switch member is pivotally mounted at 65 on the 15 adjacent surface of the casing 13 and is held in engagement with a pair of stationary contact members 66 and 67 by reason of the action of a spring 68, except when the switch is opened by the action of the cam 62. A 20 weight 69 suspended from a point 70 of the sheave tends to prevent the rotation of the sheave and of the frame 57 and causes it to return to its initial position upon reversal of the shaft after actuation of the limit stop.

25 My present invention is particularly concerned with the control of the motor but before describing the control system which embodies the motor and is illustrated in Fig. 2, I will describe the operation of the mechanism itself.

The base 10 is provided with a pair of lugs 72 which extend in opposite directions from its ends through which foundation bolts or screws may pass into the bridge, with which 35 the mechanism is specially designed to be used. The fact that but two foundation bolts are used is important for the reason that bridges of this character are often more or less distorted by the impact of the ferry 40 boats striking on one side harder than on the other. The base will not be strained by such distortion as it would be if more than two holding bolts or screws were used. A flexible rope or cable (not shown) is partially wound on the drum 15 and has a hook or other suitable fastener by which it is secured to an approaching boat. Assuming that the motor is coupled to the shaft 20, and that the lever 40 occupies the position 45 shown in Fig. 1, the motor may be operated to haul in on the cable and bring the boat into contact with the bridge.

As hereinafter pointed out, in connection with a description of the controller, the 55 motor is arranged so that it can be stalled without injury and consequently it continues to exert a holding force upon the boat after it is fast. The fact that the gear cannot overhaul the worm shaft effectively prevents 60 any reverse movement of the cable so that the boat will be held in the position into which it is thus drawn.

The opposing force exerted by the reaction of the boat and cable on the one hand 65 and the pull of the motor on the other hand

causes the worm and worm wheel to be locked so that a considerably increased torque is required when the motor is first operated in the reverse direction to release the gears and pay out the cable.

If the motor is out of commission or it is desirable for any reason to operate the mechanism by hand, the lever 40 is shifted from the position shown to its opposite extreme position thereby separating the clutch members 24 and 26 and throwing the bevel gear 25 into mesh with the gear 39. The hand wheel 45 is then operatively connected to the drum and may be utilized for hauling in or paying out the cable.

80 Referring to Fig. 2 of the drawings, the motor 11 as here shown diagrammatically, comprises an armature 80 and a series field magnet winding 81. It is supplied with energy from any suitable source through 85 line conductors 82-83 and a line switch 84. The direction of motor rotation is determined by reversing switches 85 and 86 which are governed by a master switch 87. In one direction of rotation, the motor circuit includes an adjustable resistor 88 of relatively low resistance while in the other direction of motor rotation the motor circuit includes a motor starting and regulating resistor 89 of relatively high resistance a portion of 90 which may be adjusted by hand. The limit switch 64 is arranged to interrupt the control circuit in one direction of operation, the regulating section of the resistor 89 having 95 sufficient resistance to hold the motor current at a safe value even when the motor is stalled in the reverse direction.

100 The circuit connections for the system are as follows: Assuming that the line switch 84 is closed as shown, and that the master switch 87 is thrown into position α , a control circuit is completed from conductor 90 through a movable contact arm 91, and a stationary contact member 92 of the master switch, a conductor 93, contacts 66 and 67 of the limit switch which are bridged by its 105 arm 64, magnet coil 94 of the reversing switch 86 and a conductor 95 to the supply circuit conductor of opposite polarity. The magnet coil 94 when energized causes contacts 96 and 97 to be bridged thereby completing the motor circuit from the conductor 90 through contacts 96, conductor 98, through the armature 80 in the direction of arrow α , a conductor 99, the resistor 88, a conductor 100, 110 contacts 97 which are now bridged, a conductor 102, and the field winding 81, to the conductor 95. The rotation imparted to the motor under these conditions will be transmitted to the drum in its unwinding direction. As but little resistance is in the motor circuit a high torque will be developed which 115 is sufficient to unlock the worm and its gear if they have been jammed together. This torque may be adjusted by setting a movable 120

contact arm 117 in engagement with one of the stationary contacts 118. After a desired amount of the rope or cable has been paid out, the limit switch 64 will be opened and the motor and its connected drum will stop. Obviously the point at which the automatic limit switch will act may be varied at will by simply changing the position of the nut 59.

If the master controller is moved to its position *y*, a control circuit is first established from the conductor 90, through contacts 91 and 103, conductor 104, and a coil 105 of reversing switch 85, to the conductor 95. The reversing switch 85 when closed, completes a circuit from the conductor 90 through contacts 106 of the reversing switch, the resistor 89, conductor 99, through the armature 80 in the direction of the arrow *b*, circuit a high torque will be developed which conductor 98, contacts 107, conductor 102, and field magnet winding 81 to the conductor 95. Immediately following the completion of the control circuits and motor circuits above traced, a control circuit is completed from conductor 90 through contacts 91 and 110 of the master switch, conductor 111 and a coil 112 to conductor 95. The coil 112 when energized moves a contact arm 113, over stationary contacts 114 and short circuits the starting section of the resistor 89 step by step. The remainder of the resistor 89 which determines the torque of the motor may be adjusted by setting a contact member 115 in engagement with one of the stationary contact members 116, thereby short circuiting a greater or less proportion of the adjustable section of the resistor 89. Under these conditions the motor will rotate the drum in its winding direction to haul in the boat. When the boat reaches the landing the motor will be stalled but the resistance in circuit with it is high enough to prevent injurious effect.

It is thus apparent that with the controller above described, the mechanism is capable of operating for the purpose specified, without injury to the motor and having once set the adjustable contact arms 115 and 117, the operator has only to throw the master switch 50 into its proper position or from one position to the other, depending upon the operation desired.

The form of specific circuit connections of the control system is not essential to my invention and another controller or other controllers as for example those of the drum type may be utilized in lieu of the reversing switches at the master switch.

What I claim is:

1. In combination with a reversible electric motor adapted to be operatively connected to a winch drum, non-overhauling gears between the motor and the winch drum a controller having a non-circuit closing position and comprising a reverser, and

means for limiting the motor torque in one direction of motor rotation, to a relatively low value, such that the motor may be stalled without injury when operating in said direction, said motor being adapted to exert a relatively high torque in the opposite direction to free the gears of the winch drum. 70

2. In combination with a reversible electric motor adapted to be operatively connected to a winch drum, non-overhauling gears between the motor and the winch drum a controller having a non-circuit closing position and comprising a reverser, a resistor in one direction of motor rotation for limiting the motor torque to a relatively low value to permit the motor to be stalled without injury when operating in said direction, said motor being adapted to exert a relatively large torque in the opposite direction to free the gears of the winch drum. 75 80 85

3. In combination with a reversible electric motor adapted to be operatively connected to a winch drum, non-overhauling gears between the motor and the winch drum a controller having a non-circuit closing position and comprising a reverser, means for limiting the motor torque in one direction of motor rotation to a relatively low value, such that the motor may be stalled without injury when operating in said direction, said motor being adapted to exert a relatively high torque in the opposite direction to free the gears of the winch drum, and means for automatically stopping the motor at a predetermined limit only when 90 95 100 105 110 115 120 125 130

rotating in the direction in which it has the relatively large torque.

4. In combination with a reversible electric motor adapted to be operatively connected to a winch drum, non-overhauling gears between the motor and the winch drum a controller having a non-circuit closing position and comprising a reverser, a pair of motor circuits established by the reverser, an adjustable resistor of relatively high resistance in one of said circuits to limit the motor torque to a relatively low value in one direction of motor rotation, an adjustable resistor of relatively low resistance in the other motor circuit, and means for automatically stopping the motor at a predetermined limit when rotating in the direction in which it has the relatively large torque. 115

5. In combination with a reversible electric motor adapted to be operatively connected to a winch drum, non-overhauling gears between the motor and the winch drum a controller having a non-circuit closing position and comprising a reverser, a pair of motor circuits established by the reverser, a resistor for limiting the motor current and torque for driving the winch in a hauling-in direction, to a relatively low value, to permit the motor to be stalled with- 130

out injury when the winch is hauling-in, and a resistor of relatively low resistance for driving the winch in an unwinding direction whereby the motor is adapted to exert 5 a relatively large torque for freeing the gears when the winch is operated in a paying-out direction.

In witness whereof, I have hereunto set my hand this 22nd day of March in the year 1913.

ARTHUR T. PRESCOTT.
